H. C. BRANCH

AMPLIFIER ADAPTER FOR TELEPHONES

Filed June 12, 1922

FIG. 1.

INVENTOR
Harry C. Branch
BY Ray A. Peke
ATTORNEY

UNITED STATES PATENT OFFICE.

HARRY C. BRANCH, OF CLEVELAND, OHIO, ASSIGNOR TO THE TEAGLE COMPANY, OF CLEVELAND, OHIO, A CORPORATION OF OHIO.

AMPLIFIER ADAPTER FOR TELEPHONES.

Application filed June 12, 1922. Serial No. 567,769.

To all whom it may concern:

Be it known that I, HARRY C. BRANCH, a citizen of the United States, residing at Cleveland, in the county of Cuyahoga and State of Ohio, have invented certain new and useful Improvements in and Relating to 5 Amplifier Adapters for Telephones, of which the following is a specification, reference being made therein to the accompanying drawing.

The invention relates to means for acoustically and mechanically connecting the receiver of a telephone with the small end of a horn, or other sound amplifier, to the tone 15 arm of a phonograph, for example, the invention being especially advantageous in connection with the telephone receivers of wireless telephone sets.

The chief objects of the invention are 20 comprehended in the provision of a simple, unitary and inexpensive coupling device by which telephone receivers of various shapes and sizes can be easily and effectively connected acoustically to various forms of 25 phonograph tone arms or other amplifiers.

The preferred embodiment of the invention is shown in the accompanying drawing, in which

Fig. 1 is a plan view of the main parts of 30 a phonograph with its sound box removed and a telephone receiver acoustically connected to the small end of the tone arm by means of my improved adapter.

Fig. 2 is an enlarged central longitudinal 35 section of the adapter.

Fig. 3 is an enlarged end view of the adapter.

Fig. 4 is an enlarged horizontal axial section of the adapter as mounted in Fig. 1, 40 with the telephone receiver and the end of the tone arm shown in elevation.

Fig. 5 is a view similar to that in Fig. 4 with the adapter applied to a different form of phonograph tone arm.

Referring in detail to the construction 45 illustrated and, at the outset, to the form of construction shown in Figs. 1 to 4, inclusive, 1 designates the case of a Victor phonograph, 2 the record turn table and 3 the tone arm having the U-shaped small end 3^a, the phonograph sound box and needle having 50 been detached from the tone arm. The large end of the tone arm 3 is connected in the well-known manner with the phono-

graph horn or amplifier, not shown. 4 is a 55 telephone receiver which is of the type used for head sets as commonly employed by wireless telephone and telegraph operators and telephone switch-board operators. A conductor cable 5 leads from the terminals 60 of the receiver 4 to the line receiving or transmitting the electrical impulses.

As shown in Figs. 1 and 4, the telephone receiver 4 is connected to the end 3^a of the phonograph tone arm by means of my improved adapter 6. This adapter, which is in the nature of a tubular coupling device, is in the form of a unitary molding of vulcanized soft rubber. It is formed at one end 65 with a relatively large section 6^a having an opening adapted to receive and snugly grip the peripheral bead or flange of the diaphragm end of the telephone receiver. The rubber of which the adapter is made is capable of stretching considerably and the 70 adapter is thus capable of fitting practically any of the standard telephone receivers, said receivers differing somewhat in diameter. The other end 6^b of the adapter is made 75 smaller than the end 6^a and between the two 80 ends the adapter is formed with an intermediate reduced part or neck 6^c. The opening or passage through the reduced part 6^c is 85 of a size adapting it to receive the small end of the tone arm of the Victor phonograph and others, such as the Cheney, whose tone arm ends are comparable in size to that of the Victor. The elasticity of the rubber enables it to fit and snugly hold in the part 90 95 tone arms differing materially in size.

However, the ends of the tone arms of some of the widely used makes of phonographs, such as the Columbia and the Edison, are very much larger in diameter than the ends of the tone arm of the Victor 95 phonograph. Accordingly I form the adapter 6 with the end 6^b having its passage or opening of a diameter adapted to receive and snugly grip the ends of the tone arms of such phonographs as the Columbia and the Edison. In Fig. 5 I show the adapter applied to a telephone receiver and the end of the tone arm 7 of a Columbia phonograph.

It will be seen that the adapter comprises 105 a relatively large section 6^a designed to hold the telephone receiver and a smaller section made up of the end 6^b and intermediate neck

6^c, the smaller section by reason of the different sizes of its passages or openings being adapted to fit a considerable range of sizes and shapes of tone arms or amplifiers. The 5 adapter has its walls made with a very considerable thickness and is thereby adapted to sustain the weight of the telephone receiver and effectively hold the receiver in various operative relations to the tone arm or corresponding part of the horn or other amplifier to which the adapter is attached.

The method of applying and using the adapter will readily be understood. The telephone receiver is easily forced into the 15 larger end of the adapter and the latter can then be readily applied to the small end of the phonograph tone arm or other amplifier. The result is a highly effective acoustic and mechanical coupling of the telephone receiver to the amplifier so that the sounds emitted from the disc of the diaphragm of the receiver are effectively amplified and the receiver is firmly supported by the adapter in any desired position. As the 20 adapter has no metal parts there is no possibility in its use of metallic vibrations or chatter.

By reason of the elasticity of the material of which the adapter is made it is practically 30 universal in its adaptability to fit the different standard telephone receivers and the various popular makes of phonographs and various sizes and forms of amplifier horns. Obviously, the adapter is exceedingly simple 35 and capable of being produced at a relatively small cost.

While the form of the adapter shown in the drawings is that which I have found most satisfactory, where the adapter is intended 40 for use only with tubular members or phonograph tone arms such as that of the Victor phonograph, it is obvious that the end section 6^b of the adapter is superfluous and can be omitted. It will also be obvious that 45 the form of the adapter can be varied in other respects without departing from the

invention, the scope of the invention being indicated by the appended claims.

What I claim is:

1. A device of the character described 50 comprising a molded soft rubber tubular coupling formed at one end with a large section adapted to embrace and snugly grip the peripheral flange of the diaphragm end of a telephone receiver and also formed with a 55 smaller section having its passage adapted to receive and snugly grip the end of a tubular member, the walls of said coupling being thick enough to sustain the weight of the telephone receiver and firmly hold said receiver in any desired position.

2. A device of the character described comprising a molded soft rubber tubular coupling formed at one end with an opening 60 adapted to embrace and snugly grip the peripheral flange of the diaphragm end of a telephone receiver and with the remainder of its passage having a plurality of different diameters adapted to receive and snugly grip 65 the ends of tubular members of different 70 sizes, the walls of said coupling being thick enough to sustain the weight of the telephone receiver and firmly hold said receiver in any desired position.

3. A device of the character described 75 comprising a molded soft rubber tubular coupling formed with one end larger than the other and with a reduced intermediate part, the coupling at its larger end being 80 adapted to receive and snugly grip the peripheral flange of the diaphragm end of a telephone receiver and at its smaller end and the reduced intermediate part being adapted alternately to receive and snugly grip the 85 ends of tubular members of different sizes, the walls of said coupling being thick enough to sustain the weight of the telephone receiver and firmly hold said receiver in any desired position.

In testimony whereof, I hereunto affix my 90 signature.

HARRY C. BRANCH.
